UNITED STATES PATENT OFFICE.

CHARLES W. NICHOLAS, OF TARENTUM, PENNSYLVANIA, ASSIGNOR TO WALTER P. MURPHY, OF CHICAGO, ILLINOIS.

UNCOUPLING DEVICE.

Application filed September 9, 1920. Serial No. 409,169.

To all whom it may concern:

Be it known that I, CHARLES W. NICHOLAS, a citizen of the United States, residing at Tarentum, in the county of Allegheny and 5 State of Pennsylvania, have invented new and useful Improvements in Uncoupling Devices, of which the following is a specification.

This invention relates to uncoupling devices for car couplers generally but more particularly to such devices for locomotives in which use it is highly desirable that the device may be operated from both sides of the locomotive.

10 The object of this invention is to provide an uncoupling device, which may be operated from either side of the car and of such construction that the operating handles will not project forward from the end of 15 the car when the lock pin of the coupler is in lock set position, means being provided to permit the handle to return to its normal substantially vertical position against the end of the car. In some types of uncoupling 20 devices the operating handle remains in its raised position when the lock pin is in lock set position, which in the case of use on a locomotive is very dangerous, inasmuch as operators in stepping from the foot board, 25 usually found on front boards of locomotives, are liable to have their clothing caught in such an outstanding handle whereby they 30 may be thrown on the track and injured. These conditions make it desirable to provide 35 means whereby the handle operated may return to its normal substantially vertical position, without disturbing the lock set position of the lock pin.

This invention consists of a single operating lever mounted on the car having operating handles on opposite sides of the coupler and a crank at the center of the lever extending forwardly from the car and substantially at right angles to the handle, a 45 rigid bar link connected to the lock pin of the coupler at its lower end and vertically slidably connected at its upper end with said crank whereby all service movements of the coupler are permitted without imposing 50 strains upon the lever and whereby the operating lever may return to its normal position without disturbing the lock set position of the coupling pin.

In the drawings:

55 Figure 1 is a top plan view of the end

structure of a car with this invention in operative position thereon.

Figure 2 is a front elevation of Figure 1.

Figure 3 is a side elevation of Figure 1.

Figure 4 is an enlarged detail plan view 60 of a crank clip shown in position on the crank.

Figure 5 is a view in side elevation of Figure 4.

Figure 6 is a view in section taken on the 65 line 6—6 of Figure 4.

Figure 7 is an enlarged detail top plan view of a modified form of crank clip.

Figure 8 is a view in side elevation of Figure 7.

Figure 9 is a view in section taken on the 70 line 9—9 of Figure 7.

The reference numeral 1 designates an end structure for a car or locomotive. For convenience the term "car" will be understood 75 to include locomotives, the coupler 2 with this lock pin 3 may be of the improved automatic type, now commonly in use.

The operating lever 4 is formed in one continuous bar provided at the ends with depending handles 5 which terminate at their lower ends in a rearwardly bent position 6 spaced from the handle and adapted to normally lie against the end structure, thereby spacing the handle 5 from the end structure, 85 thus, eliminating all danger of the operator having his hand crushed between the handle and end structure. The center of the operating lever is provided with an integral crank 7 formed by bending the lever bar 90 upon itself so that the crank extends forwardly from the end structure of the car, substantially at right angles to the handle and terminating at its end with an eye 8.

Brackets 9 are secured near each end of 95 the end structure and are provided with filler pieces 10 and cotter pins 11. A double bracket 12 is secured midway of the ends of the end structure. The center bracket 12 is also provided with filler blocks 13 and 100 cotter pins 14.

The coupler lock pin 3 is connected to the crank 7 of the lever by means of a rigid bar link 15 which comprises a hook 16 at its lower end, the end of which is deflected from 105 the plane of the rest of the body of the hook whereby it may, without the use of tools, be engaged with and disengaged from the eye of the coupler lock pin only when the lever 4 is removed from its bracket. The 110

rest of the rigid link comprises an arm or bar extending upward from and integral with the hook and terminating in an open forwardly extending hook 17 which passes 5 through the eye 8 of the crank and is free to slide vertically relatively to said eye and is free to move vertically to said eye to accommodate all service movements of the coupler. The engagement 10 between the hook 17 and the eye 8 of the lock pin being such as will also permit of such movement without imposing strains upon the operating lever.

To prevent the bent back portions of the 15 crank 7 from spreading and to form a bearing in the eye 8 for the link 15 a clip 18 is provided having a tongue 19 extending into the eye and downwardly extending sides 20 adapted to be secured about the portions of 20 the crank to rear of the eye where they contact. The clip may be of one piece and pressed into position as shown in Figures 4, 5 and 6 or may be in two pieces 21 and 25 22 engaging opposite sides of the crank or bolted or riveted in place as shown in Figures 7, 8 and 9.

The operation is as follows: To uncouple the cars or to place the lock pin in lock set position, the operator pulls forward on 30 either one of the handles of the lever thereby revolving it in its brackets and elevating the crank causing the eye of the crank to move up into engagement with the hook of the rigid link, elevate the link, and pull the 35 lock pin of the coupler into lock set position, after which the handle is liberated and it will automatically fall to its normal position against the end structure without disturbing the lock set position of the lock pin.

40 What I claim is:

1. In a release rigging for car couplers,

an operating lever comprising a rotatable bar mounted upon the end of the car and extending from side to side thereof, integral handles depending from each end of the 45 lever and an integral crank extending centrally from the lever substantially at right angles to the handles formed by bending the rod back upon itself and leaving an eye in the outer bend, and a rigid link passing 50 through the eye of the crank having an open hook at its lower end adapted to engage the lock pin of the coupler and a stop on its upper end adapted normally to prevent disengagement from the crank, and a 55 clip having a tongue entering the eye of the crank and side members adapted to engage the portions of the rod where they contact at the rear of the eye, said clip acting as a bearing for the link in the eye and as a 60 binding member to prevent the portions of the rod from spreading at the rear of the eye.

2. An operating lever for a release rigging for car couplers comprising a bar 65 adapted to be rotatably mounted upon the car end and extending from side to side thereof, integral handles depending from each end of the lever and an integral crank extending centrally from the lever substantially at 70 right angles to the handles formed by bending the rod back upon itself and leaving in the outer bend an eye adapted for the passage of a pin lifter link, and a clip having a tongue entering the eye of the crank 75 and side members adapted to engage the portions of the rod where they contact at the rear of the eye, said clip acting as a bearing for the link in the eye and as a 80 binding member to prevent the portions of the rod from spreading at the rear of the eye.

CHARLES W. NICHOLAS.
